LINOTYPE-MACHINE.

No. 838,062.

Specification of Letters Patent.

Patented Dec. 11, 1906.

Application filed October 5, 1905. Serial No. 281,458.

To all whom it may concern:

Be it known that we, FREDERICK WILLIAM SUTCLIFFE, of London, and CHARLES HOLLIWELL, of Broadheath, England, have invented new and useful Improvements in Linotype-Machines; and we do hereby declare the following to be a full, clear, and exact description of the invention, such as will enable others skilled in the art to which it appertains to make and use the same.

This invention relates to improvements in linotype-machines; and it consists in mechanism which enables the machine to cast linotypes of different lengths from the same composed line of matrices and spaces. It is particularly applicable for use on the Mergenthaler linotype-machine described in the specification of Letters Patent No. 436,532, September 16, 1890.

The particular users of linotype-machines who have already and will in the future find this invention useful are those who supply stereotypes to the printing trade, and some of whose customers require their stereotypes to have lines of one length, while other customers require their stereotypes to have lines of a different length. For instance, let it be supposed that one such customer is the proprietor of a newspaper having lines thirty ens long, while the lines of another customer's newspaper are only twenty-eight ens long. It is obvious that a thirty-ens stereoty whole cannot be cast from a flong made on twenty-eight-ens linotypes nor a twenty-eight-ens one from a thirty-ens flong, and even if the user were to set the job in movable type instead of in linotype there would still be the necessity of "running over" the lines after the first flong had been taken from them to shorten them from thirty ens to twenty-eight ens or to lengthen them from twenty-eight ens to thirty ens, according to which of the two had been their original length, before the second flong could be taken.

The present invention makes the linotype-machine practically run over each twenty-eight-ens line of matrices and space-bars after the twenty-eight-ens linotype has been cast from it and lengthen it to thirty ens, so that the machine can cast a thirty-ens linotype from the said line before it is distrib-

uted, thereby obviating the necessity of a separate composition for each length of linotype.

It consists in combining a filling-piece with the vise that holds the composed line during the acts of justification and casting, the said filling-piece having an operative thickness equal to the desired difference in the two lengths of linotypes. The vise is adjusted for the longer length and this length reduced to the shorter one by the insertion of the filling-piece. The line is then composed as for the shorter length, but more "tightly" (as it is called) than usual for the following reason. This reason will be most readily understood if it is explained in connection with a Mergenthaler space-bar. Each space-bar of a Mergenthaler linotype-machine is a double wedge capable of being thickened by having one of its wedges slid along over the other, the thickening increasing as long as the sliding continues. In the commercial machine of to-day this thickening continues until the line is justified. Consequently the more matrices there are in a line the less need there is for each space-bar to be thickened to its maximum to justify the line. It is quite possible for an operator to compose so few matrices into the line that the justification of it will absorb all the justifying capacity of its space-bars. This sort of composition, known as "loose," will not satisfy the present invention, because there must be a reserve of justifying capacity equal to the difference between the two lengths of linotypes. This is why the present invention requires that the line should be composed more tightly than usual, for a line so composed will be justified before the space-bars are thickened to the maximum, thereby providing the required reserve of justifying capacity.

After the shorter linotype has been cast the filling-piece is withdrawn from the vise, thereby leaving it adjusted for the longer length. The composed line is again placed in the vise, and after it has been justified to the longer length the longer linotype is cast and the composed line distributed.

The filling-piece may be alternated—*i. e.*, inserted and withdrawn—by hand; but to do this with the necessary regularity would tax,

the attention of the operator, so that such manual operation is practically impossible. That being so, the invention includes automatic alternating mechanism for inserting and withdrawing the filling-piece. These means may be of any suitable kind and be actuated by any regularly-moving part of the machine. The mold-carrier is fitted with two molds, one of the longer and one of the shorter length. Any of the molds adjustable for length—such as those of Patents No. 562,751, June 23, 1896, or No. 539,993, May 20, 1895—may be used; but their adjustability is not to meet the change from the longer to the shorter length—say from twenty-eight to thirty ens—but to meet the change from one range of lengths to another, as when the lengths are, say, forty-eight and fifty ens instead of twenty-eight and thirty ens. It is always the filling-piece that provides for the difference between the two lengths.

In the accompanying drawings, Figure 1 is a front elevation; Fig. 2, a plan; Fig. 3, a side elevation of the abutment and filling-piece, taken on the line 3 3 of Fig. 2 looking at it in the direction of the arrow; and Fig. 4, a diagram of one cycle of the invention. Fig. 5 is a side elevation, and Fig. 6 a plan, of the automatic repeating mechanism. Fig. 7 is a side elevation of the automatic means for justifying the composed line to the respective lengths after each presentation of the said line to the mold.

1 is the shorter-length mold, and 2 is the longer-length mold, both mounted diametrically opposite to each other on the mold-carrier 3 in the well-known way. This carrier, known as the "mold-wheel," is rotated by gearing from the cam-shaft of the machine in substantially the same way as heretofore, but with the following difference:

In the ordinary commercial machine only one mold is in use on one job, the other mold (or molds, for there are sometimes as many as four on the wheel) being in reserve to be used on jobs requiring shorter or longer or thicker or thinner linotypes, and the mold turns through two arcs, one of ninety degrees and one of two hundred and seventy degrees, 45 for each linotype cast, with a rest between each arc, the driving-gear on the cam-shaft being mutilated to provide these rests; but for the purpose of the present invention the carrier 3 must make half a revolution for each linotype cast, because it must present the two molds 1 2 successively opposite the composed line when it is in the vise each time the machine is ready to cast. Consequently the mutilated gear on the cam-shaft consists of 50 two equal arcual racks of about forty-five degrees each set opposite to each other with equal rest-surfaces between them. A mold is in the casting position when it is stationary behind the vise and close up to it, as

shown in Figs. 1 and 2 with reference to mold 1.

4 is the fixed, and 5 the movable, vise-jaw; 6, the abutment for the jaw 5, engaged and operated by the screw 7 to hold the jaw 5 at the proper distance from the jaw 4 and 8, 70 the vise-frame supporting the parts 4, 5, 6, and 7. The distance shown in Figs. 1 and 2 between the jaws 4 and 5 is the usual vise-opening to receive the composed line of matrices and space-bars. This line is omitted 75 from the figures, so as not to obscure the co-operation between the vise 4, 5 and the two molds 1, 2. The filling-piece consists of a slide 9, working, by means of a dovetail 10, in a groove 10^a in the right-hand face of the 80 abutment 6.

11 is a pin fast to the slide 9 and projecting laterally from it through a cavity 12 in the adjacent face of the abutment 6 and entering a block 13, sliding in a bore 14 in the rear 85 face of the said abutment. The cavity 12 is long enough from front to rear to allow of the movement of the slide 9 in the abutment 6.

15 is a spring resilient between the front face of the block 13 and the closed front end 90 of the bore 14, so that the slide 9 is always being urged to the rear.

16 is a plate to close the rear face of the bore 14.

17 is a nose on the rear end of the slide 9, 95 adapted either to be engaged by the mold-carrier 3 when the latter is moved to the front as heretofore to make its mold fit up metal-tight against the composed line of matrices and space-bars in the vise or to allow a hole 10^a 18 in the mold-carrier 3 to pass over it, so that the motion of the said carrier to the front shall not affect the filling-piece. The hole 18 is so positioned in the mold-carrier 3 that when the shorter-length mold 1 is in casting 105 position the hole 18 is diametrically opposite the nose 17 and when the longer-length mold 2 is in casting position it registers with the said nose. The operative surface of the filling-piece is shown as consisting of a pair of cams 110 19, 19 on the side of the slide 9 next to the vise-jaw 5, each cam merging in a flat surface 20 to the rear of it. The projection of a cam 19 and its surface 20 from the slide 9 is equal to the difference in length between the two 115 molds 1 and 2. The slide 9 is always in contact with the abutment 6 on one side and with the jaw 5 on the other, so that its presence in no way interferes with the control of the screw 7 over the position of this jaw 5. The 120 rear cam 19, with its surface 20, is positioned on the slide 9 just far enough to the rear to clear the jaw 5 when the hole 18 is over the nose 17.

21 is a cavity in the adjacent face of the jaw 125 5 to stand over the front cam 19 and its surface 20 when the rear cam and its surface are clear of the jaw 5. Both cams 19 and their

surfaces 20 are either in engagement to the same extent and at the same time with the jaw 5 or out of engagement with it. The reason why there are two cams 19 and surfaces 20 is that the engagement between the slide 9 and the jaw 5 would not be symmetrical if there were only this rear cam and surface. To make such engagement symmetrical, the front cam 19 and its surface 20 are added.

10 The automatic means for justifying the line first to the shorter length and afterward to the longer length is the justifying mechanism in general use to-day in the commercial linotype-machine and is illustrated 15 in Fig. 7.

150 151 are two cams fast on the cam-shaft 31 of the machine, and therefore turning with it in the direction indicated by the arrow.

150^a 151^a are the two justifying-levers. They are both fulcrumed on a common fulcrum 152 in the machine-frame 30. Each carries an antifriction-roller 150^b 151^b, and both rollers are kept in contact with the respective peripheries of the cams 150 151 by springs 150^c 151^c and push-rods 150^d 151^d, having collars 150^e 151^e fast on them, and between which collars and the base of the machine-frame the said springs are constantly in compression, and therefore always holding 25 the front ends of the levers 150^a 151^a as high as the respective contacts between the peripheries of the cam 150 151 and the rollers 150^b 151^b allow them to do. The front ends of the cam-levers 150^a 151^a are loosely connected to the bottom ends of vertical rods 150^f 151^f, respectively. These rods are capable of sliding in suitable fixed guides as the respective levers rise and drop under the joint action of the cams 150 151 and springs 30 150^c 151^c. These two rods 150^f 151^f show in the figure as one behind the other. Their top ends are pivotally connected to a justifying-plate 153, which stands under the opening between the vise-jaws 4 5. It is into 35 this opening that the first elevator 22 puts the composed line of matrices Y and space-bars. All the matrices and space-bars hang in the head of the said elevator 22 by lugs which engage in grooves 154 in the said head, as shown 40 in the figure. Only the lugs *y* of one matrix show in the figure, those of the other matrices, as well as those of the space-bars, being behind. A space-bar has been already described as being a double wedge capable of 45 being thickened by having one of its wedges slid along over the other. These two wedges are of different lengths, one of them being shorter than a matrix and the other being much longer. It is the shorter wedge that. 50 carries the lugs *z*, by which the space-bar is suspended from the grooves 154, and that is why the shorter wedges do not show in the figure. One longer wedge *Z* shows projecting downward below the composed line of

matrices and space-bars, (and also above it, 65 because the figure illustrates a justified position,) the other long wedges being behind it. At the moment that the elevator 22 puts the composed line in the vise-opening the rises of the two cams 150 151 hold the front ends of 70 the levers 150^a 151^a, and consequently the justifying-plate 153, in their lowest respective positions; but by the time the said line is to be justified the rotation of the cams has placed their drops—say the two *a a*—opposite the two lever-rollers 150^b 151^b, so that the springs 150^c 151^c at once push the said justifying-plate 153 up, making each longer wedge slide over its shorter fellow wedge, thereby thickening each space-bar as much as the then 80 distance between the jaws 4 and 5 permits of. This is the condition shown in the figure. There are two drops *a b* (and consequently two rises) shown in each cam, because there are two in each cam in the commercial linotype-machine; but this duplication is a detail that does not concern the present invention, for as far as it is concerned each cam may be considered as having only one rise and one drop, the rise and drop in one substantially registering with the rise and drop in the other and both rises and both drops acting once only during each rotation of the cam-shaft 31.

The invention works as follows: Assuming 95 that the two desired lengths of linotypes are twenty-eight and thirty ens, the molds 1 and 2 are set to these lengths, respectively, a slide 19, having a cam projection of two ens, mounted in the abutment 6, and the screw 100 7 adjusted in the abutment to hold the jaw 5 at the longer length (thirty ens) from the jaw 4. As the shorter linotype is cast before the longer one, the mold 1 is on the right and the longer one, 2, on the left when the machine is 105 at rest I of Fig. 4, the hole 18 being about ninety degrees behind the mold, Fig. 2. It is therefore not opposite the nose 17 of the slide 9. The carrier 3 being now clear of the said nose 17, the latter is held protruded by 110 the spring 15, Fig. 2. The machine is started, and the well-known first elevator 22, Fig. 2, puts the line of matrices and space-bars, composed tight, as already explained, in the vise between the jaws 4 5, and the first cam-rack turns the mold 1 up opposite the composed line, Fig. 1 and II of Fig. 4, and leaves it there. The mold-carrier 3 is next pushed to the front, as heretofore, to make the face of the mold 1 contact metal-tight with the 115 composed line, Fig. 2. In so doing the solid front face of the carrier 3 engages the nose 17 and pushes the slide 9 to the front, thereby making the cams 19 push the jaw 5 nearer to the jaw 4 by two ens, in which position the 120 screw 7 will hold it fixed, the slide 9 being pinched between the abutment 6 and the jaw 5, whereby it becomes practically an ex-

tension of the said abutment. The composed line is now justified in the ordinary way; but as it was composed "tight" not more than about half of the justifying capacity of the space-bars in it is used up. The shorter linotype is then cast and the carrier 3 moved to the rear, as heretofore. This motion clears the slide 9, which is immediately pushed to the rear by the spring 15. The second cam-rack now turns the carrier 3 through ninety degrees, III of Fig. 4, thereby putting the mold 2 opposite the well-known ejector and leaving it there. The ejector now acts in the usual way; but as the mold 2 is empty this particular action of the ejector is an idle one. The cam-shaft has now completed one rotation. The first rack now turns the carrier through ninety degrees, IV of Fig. 4, thereby putting the mold 2 in the casting position and the hole 18 opposite the nose 17. The distribution of the composed line, which would have been begun by the machine by this time, is prevented by the repeating mechanism, (illustrated in Figs. 5 and 6 and described further on,) the line itself being practically left in the vise. (As a matter of fact, it is taken out of the vise as if it were going to be distributed and then returned to it.) The carrier 3 is then pushed to the front, and as the hole 18 passes over the nose 17 without touching it the cams 19 19 remain stationary in the position which the spring 15 had pushed them into, thereby leaving the jaw 5 at the longer distance (thirty ens) from the jaw 4. The line is now justified to the longer length, the reserve of justifying capacity in the space-bars in it being used up for that purpose. The longer linotype is then cast. Next the second rack turns the carrier 3 through ninety degrees, V of Fig. 4, leaving the mold 1 with the shorter-length linotype in it opposite the ejector, which thereupon ejects it. The longer linotype having been cast, the composed line is distributed in the usual way. The cam-shaft has now completed its second rotation. This completes a cycle of the invention, or, to speak quite correctly, it would do so if there had been a linotype in the mold 2; but as there is not the carrier 3 must be turned through two more arcs of ninety degrees each to complete it; but all the subsequent cycles will be completed in two rotations of the cam-shaft. During each cycle the operator has been composing the next line, and this is placed in the vise in time to coöperate with the mold 1 each time that it comes opposite the vise. Thus the machine delivers first a shorter linotype and next a longer one, both cast from the same composed line.

Figs. 5 and 6 illustrate an improved form of the repeating mechanism that prevents the removal of the composed line by the well-

known distributor after the shorter linotype 65 has been cast, the return of the line to the casting position effected, and the distribution of it after the longer linotype has been cast permitted. This mechanism is practically identical with the invention described in the specification of Letters Patent No. 645,472, March 13, 1900, and therefore *per se* forms no part of the present invention. 60 is a cam fast on the cam-shaft of the machine; 61, a portion of the lever mechanism that normally takes the composed line out of the first elevator 22, Fig. 2, preparatory to the distribution of it, and which mechanism is actuated by the cam 60 in one direction and by a spring (not shown) in the other; 62, a lever 80 fulcrumed on the machine-frame at 63 and adapted to stop the cam-shaft after a linotype has been cast; 64, a wedge-shaped projection fast on the lever 62; 65, a radial projection on the periphery of the cam 60; 85 66, a shaft turning in stationary brackets 67 67; 68, a lever loose on the shaft 66 and made by the pull of a spring 69 to hold its nose just within the path of the projection 65 as the latter turns down toward the adjacent nose of the said lever 68; 70, a pawl pivoted on the link 68; 71, a ratchet-wheel fast on the shaft 66 and with which the pawl 70 engages to turn the shaft 66 intermittently; 72 72 72 72, four stops, and 73 73 73 73 four intermediate notches, arranged symmetrically about a boss 74 on the shaft 66 under a stud 75 on the rock-shaft 76 of the portion 61; 77, a cam likewise fast on the shaft 66, having four depressions and four 100 points symmetrically arranged at forty-five degrees from each other, the depressions being at an angle of forty-five degrees with the respective notches 73, and with which cam the projection 64 coöperates. The shaft 66 105 is set by hand, so that when a filling-piece is between the abutment 6 and the jaws 5 a notch 73 is opposite the stud 75, the projection 64 being at the same time in a depression of the cam 77. The pawl 70 is then put 110 in gear with the ratchet-wheel 71, a spring combined with the pawl keeping it in gear. As the shorter composed line is being conveyed to the vise the projection 65 comes up to the lever 68 and turns it downward about the shaft 66 through forty-five degrees, thereby making the pawl 70 turn the shaft 66 till a stop 72 is opposite the stud 75 and a point of the cam 77 in engagement with the projection 64 on the lever 62, thereby rocking the latter out of action, the consequence being that the lever mechanism represented by the portions 61 and 76 fails to take the composed line out of the first elevator 22, so that the latter returns it to the vise and the cam-shaft 115 makes a second revolution, thereby effecting the casting of the longer linotype and also moving the particular stop 72 out of the path 120 makes a second revolution, thereby effecting the casting of the longer linotype and also moving the particular stop 72 out of the path 125

of the stud 75 and a notch 73 into the path of it, so that the mechanism 61 works normally after the longer linotype has been cast, and the composed line is then distributed in the 5 usual way. When the machine is to work normally—*i. e.*, without the present invention—the pawl 70 is rocked on its pivot out of engagement with the ratchet-wheel 71.

It has already been stated that the invention is particularly applicable to the Mergenthaler linotype-machine of Letters Patent No. 436,532, September 16, 1890, and so it is; but its applicability is not limited to that machine. For instance, with reference to the 15 justifying devices which the invention relies on the essential feature is the reserve of justifying capacity. The Mergenthaler justifying devices are double-wedge space-bars acting in the direction of their length, while 20 the justifying devices of the typograph-machine are double wedges acting circularly; but the present invention is so far applicable to both machines, for the reason that the justifying devices of each possess the above-mentioned reserve of justification. Com- 25 pressible elastic justifying devices would possess such reserve of justifying capacity. So it must be clearly understood that the present invention is applicable to any machine 30 whose justifying devices possess the required reserve of justifying capacity. Further, the mold-carrier of the Mergenthaler machine is a rotating one adapted to present two molds alternately in the casting position; but it is 35 this presentation that is the essential function of the carrier. The rotation as such is immaterial, because the same presentation would be accomplished by a mold-carrier having a to-and-fro motion, either arcual or linear.

40 We claim—

1. The combination of molds; vise; filling-piece; automatic means for alternately inserting and withdrawing the latter; automatic means for presenting the composed 45 line in the casting position twice in succession; and automatic means for justifying it to the respective length after each presentation.

2. The combination of mold-carrier; two molds of different lengths; filling-piece 50 adapted to be put into operative position by the mold-carrier as it presents the shorter mold in its casting position; and automatic means for putting the said pieces out of operative position when the shorter mold is not 55 in the casting position.

3. The combination of mold-carrier; two molds of different lengths; means for presenting them successively in the casting position; vise and filling-piece; means by which the 60 mold-carrier puts the filling-piece into operative position when it presents the shorter-length mold in the casting position; automatic means for withdrawing the filling-piece from that position when the shorter-

length mold is not in the casting position; automatic means for presenting the composed line in the casting position twice in succession; and automatic means for justifying it to the respective length after each presentation. 65

4. The combination of mold-carrier; two 70 molds of different lengths mounted thereon; vise adapted to hold the composed line in the casting position and having one jaw movable to and from the other jaw; abutment adjustable to hold the movable jaw at a given distance from the said other jaw; filling-piece situated between the abutment and the movable jaw; spring to hold it in its inoperative position and in the path of the mold-carrier when the shorter-length mold is to be cast 80 from; and a hole in the mold-carrier to pass over the filling-piece when the longer-length mold is to be cast from.

5. The combination of mold-carrier; two 85 molds of different lengths mounted thereon; vise adapted to hold the composed line in the casting position and having one jaw movable to and from the other jaw; abutment adjustable to hold the movable jaw at a given distance from the said other jaw; filling-piece 90 situated between the abutment and the movable jaw; spring to hold it in its inoperative position and in the path of the mold-carrier when the shorter-length mold is to be cast from; a hole in the mold-carrier to pass over 95 the filling-piece when the longer-length mold is to be cast from; and automatic means for putting the said piece out of operative position when the shorter mold is not in the casting position. 100

6. The combination of mold-carrier; two molds of different lengths mounted thereon; vise adapted to hold the composed line in the casting position and having one jaw movable to and from the other jaw; abutment adjustable to hold the movable jaw at a given distance from the said other jaw; filling-piece situated between the abutment and the movable jaw; spring to hold it in its inoperative position and in the path of the mold-carrier 110 when the longer-length mold is to be cast from; a hole in the mold-carrier to pass over the filling-piece when the shorter-length mold is to be cast from; automatic means for presenting the composed line in the casting 115 position twice in succession; and automatic means for justifying it to the respective length after each presentation.

7. The combination of mold-carrier; two 120 molds of different lengths mounted thereon; filling-piece adapted to be put into operative position by the mold-carrier as it presents the shorter mold in its casting position; automatic means for putting the filling-piece out of operative position when the shorter mold 125 is not in the casting position; and automatic means for presenting the composed line to each mold in succession.

8. The combination of mold-carrier; two molds of different lengths mounted thereon; filling-piece adapted to be put into operative position by the mold-carrier as it presents the shorter mold in its casting position; automatic means for putting the filling-piece out of operative position when the shorter mold is not in the casting position; automatic means for presenting the composed line to each mold in succession; and automatic means for justifying the said line to the respective length after each such presentation.

In witness whereof we have hereunto set our hands in the presence of two witnesses.
